US00D747201S

(12) **United States Design Patent**
Pellerin

(10) **Patent No.:** **US D747,201 S**
(45) **Date of Patent:** **** Jan. 12, 2016**

(54) **CLOSURE**

(71) Applicant: **BERICAP**, Longvic (FR)
(72) Inventor: **Philippe Pellerin**, Dijon (FR)
(73) Assignee: **BERICAP**, Longvic (FR)
(**) Term: **14 Years**
(21) Appl. No.: **29/485,327**
(22) Filed: **Mar. 18, 2014**

(30) **Foreign Application Priority Data**

Sep. 18, 2013 (EM) 002311878
(51) **LOC (10) Cl.** **09-07**
(52) **U.S. Cl.** **D9/449**
USPC **D9/449**

(58) **Field of Classification Search**

USPC D6/542-545; D7/300, 321, 392.1,
D7/396.2, 500, 507, 509, 510, 511, 900;
D9/434-449, 452-455, 682, 685;
215/200, 235, 236, 252, 259, 329,
215/355-364; 220/200, 220, 254.1, 254.4,
220/556, 703, 704, 705; D28/4, 76, 88, 89,
D28/82, 91.1

See application file for complete search history.

(57) **CLAIM**

I claim the ornamental design for a closure, as shown and described.

DESCRIPTION

FIG. 1 is a front elevational view showing a first embodiment of a closure;

FIG. 2 is a left side elevational view showing the first embodiment;

FIG. 3 is a rear elevational view showing the first embodiment;

FIG. 4 is a right side elevational view showing the first embodiment;

FIG. 5 is a bottom elevational view showing the first embodiment;

FIG. 6 is a top elevational view showing the first embodiment;

FIG. 7 is a perspective view showing the first embodiment;

FIG. 8 is a front elevational view showing a second embodiment of a closure;

FIG. 9 is a left side elevational view showing the second embodiment;

FIG. 10 is a rear elevational view showing the second embodiment;

FIG. 11 is a right side elevational view showing the second embodiment;

FIG. 12 is a bottom elevational view showing the second embodiment;

FIG. 13 is a top elevational view showing the second embodiment; and,

FIG. 14 is a perspective view showing the second embodiment.

The features shown in discontinuous or broken lines are for illustrative purposes only and form no part of the claimed design.

1 Claim, 14 Drawing Sheets
